UNITED STATES PATENT OFFICE.

MADISON D. SHIPMAN, OF DE KALB, ILLINOIS.

BUTTON.

SPECIFICATION forming part of Letters Patent No. 350,020, dated September 28, 1886.

Application filed November 23, 1885. Serial No. 183,767. (No model.)

To all whom it may concern:

Be it known that I, MADISON D. SHIPMAN, a citizen of the United States, residing at De Kalb, in the county of De Kalb and State of Illinois, have invented certain new and useful Improvements in Buttons, of which the following is a specification, reference being had therein to the accompanying drawings, in which—

Figure 1 is a central vertical section of the head of my improved button. Fig. 2 represents in central vertical section the parts composing the head detached. Fig. 3 is a similar view of the stud complete; Fig. 4, a similar view of the parts thereof separated. Fig. 5 is a similar view of two forms of the spring when made in one piece. Fig. 6 is a similar section of a modified form of stud attached to the cloth. Fig. 7 is a similar section of the parts thereof before being united, showing also a plan view of the washer. Fig. 8 is still another modified form of stud. Fig. 9 represents a central vertical section of my improved button applied to the fabric.

My invention relates to buttons of that class in which the front and back are made detachable, and are held together, when desired, by the lateral pressure of a spring in or upon the stud; and it consists in the peculiar combinations and the novel construction and arrangement of parts more fully hereinafter described and claimed.

Referring by letter to the drawings, A designates the cap, which is preferably made of the form shown in Figs. 1 and 2, but not necessarily so, providing it has sloping sides. It is provided with a flange which extends downward when first made, as shown in full lines in Fig. 2, and is afterward turned in, as shown in Figs. 1 and 9, and in dotted lines in Fig. 2.

B is a tube or eyelet, the sides of which are preferably sloping and terminating at one end in a flaring flange, b, whose edge is turned inward.

C is a tube provided with a flange, c, as shown.

To attach this part of the button, which forms the head thereof, to the fabric, the tube C and cap A are first united by inserting the flange of the tube C in the open end of the cap, and then pressure is applied which clinches the

edge of the cap on both sides of the flange of the tube, as shown in Fig. 1. The shank of the tube C is then put through the fabric, and the shank of the tube B inserted through the fabric inside of the shank of said tube C, and then pressed together. This pressure expands and turns outwardly the end of the tube C under the flaring flange or rim b of the tube B, thus securing the fabric firmly between the rim a' of the cap A and the rim b of the tube B, as shown in Fig. 1. By this construction it will be seen that the fastening device is entirely out of sight, leaving no unsightly or rough edges to catch and tear the clothing or flesh. This manner of securing the parts together also admits of the buttons being firmly and readily attached to fabrics of varying thicknesses. The square top of the tube B also forms a shoulder for the curved ends of the spring of the stud, hereinafter described, to catch upon when the two parts of the button are engaged.

While I have described and shown the edge of the cap as clinched upon both sides of the flange c of the tube C, and prefer so to do, as it more firmly unites the parts, I do not wish to confine myself to this construction, as nearly as satisfactory a result may be obtained by clinching it upon the underside only, as shown in Fig. 9, the sloping sides of the cap forming, so to speak, a clinch on the top, and preventing the upward movement of the tube C.

In Figs. 3 and 4, D is a tube having a base consisting of an outwardly-turned flange whose edge is turned under to form an annular recess, d, as shown. E are springs, the upper ends of which are curved and the lower ends turned outwardly. F is an eyelet of ordinary construction. G is a round headed tack or plug, the function of which will soon be explained. These parts form the stud which is secured to the fabric in the following manner: The springs and plug are inserted in the tube D, as shown in Fig. 3, with the lower side of the flange of the tube resting on the top of the fabric, as shown. The eyelet is then put through the fabric, and its upper end coming in contact with the head of the plug G is spread outward between the upper and lower parts of the flange on the tube D, thus firmly securing the fabric between the flange of the

eyelet and the lower part of the flange of the tube D.

Instead of making the spring in two parts, as described, I may sometimes make it of one piece, as shown in Fig. 5, in which case the plug G is dispensed with.

In the form shown in Fig. 7 the tube D is provided with a recess, e, to receive the shoulders f of the springs H, the ends of which instead of being turned outwardly, as shown in Figs. 3 and 4, are extended to form prongs g. It is a washer, used with this form of stud in place of the eyelet. This washer, which I consider the substantial equivalent of the eyelet in the other form described, has a central elevation, i, and a turned over rim, j. This style of stud is secured to the fabric in a manner similar to that in Figs. 3 and 4, the prongs of the springs passing through the fabric and being pressed outward into the recess between the upper and lower parts of the rim of the washer, and the fabric being held between the flange of the tube and the top part of the rim of the washer. When a spring made in two parts is used, I employ a round headed plug or tack; but when I use a spring made in one piece, as shown in Fig. 6, this plug is dispensed with.

In Fig. 8 I show the ends of the springs turned under to form a recess, l, and the end of the eyelet, when the parts are pressed together, is turned outwardly by reason of its engagement with the head of the plug, and enters the recess l in the springs.

It will be observed that in each and all of the forms of stud described the fastening devices are out of sight, the same as in the head.

What I claim as new is—

1. In a separable button, the combination of the cap, a tube having a flange clinched by said cap with its lower end turned outward, and an eyelet having sloping sides at its base and a turned-over rim to receive the outturned end of said tube, substantially as and for the purpose specified.

2. In a separable button, the combination of a tube having an annular recess, a spring or springs secured in said recess and projecting through the upper part of said tube and an eyelet, substantially as and for the purpose specified.

3. In a separable button, the combination of a tube, a spring or springs projecting through said tube, a plug for securing said springs, and an eyelet, substantially as and for the purpose specified.

4. In a separable button, the combination, with the tube D, of the springs E inserted therein, and the plug G, arranged between said springs and adapted to retain them in position in said tube, substantially as described.

5. In a separable button, the combination, with the tube D, having outwardly-turned flange, of a spring-catch, a plug for holding the same in position, and an eyelet spread by the head of said plug, substantially as described.

6. In a separable button, the combination, with the tube B uniting the button to the fabric, of a spring-catch secured to a stud and engaging with the upper end of said tube, substantially as described.

7. In a separable button, the combination, with a suitable head, as the cap A, the tube C and eyelet B, of a stud consisting of a tube and a spring or springs secured therein and projecting beyond the same and adapted to pass into and be held by the head, substantially as described.

In testimony whereof I affix my signature, in presence of two witnesses, this 21st day of November, 1885.

MADISON D. SHIPMAN.
